US00D508299S

(12) **United States Design Patent** (10) Patent No.: **US D508,299 S**
 Dunn et al. (45) Date of Patent: **** Aug. 9, 2005**

(54) **PET GROOMING TOOL**

(75) Inventors: **Steven B. Dunn**, Beverly Hills, CA (US); **Bryce D. Fujii**, Canoga Park, CA (US); **Kevin C. Clark**, Los Angeles, CA (US); **Charles Davis**, Torrance, CA (US); **Zoltan Pavlakovich**, San Pedro, CA (US)

(73) Assignee: **Munchkin, Inc.**, Van Nuys, CA (US)

(**) Term: **14 Years**

(21) Appl. No.: **29/200,524**

(22) Filed: **Feb. 27, 2004**

(51) LOC (8) Cl. **30-99**

(52) U.S. Cl. **D30/158; D4/138**

(57) **CLAIM**

An ornamental design for a pet grooming tool, as shown and described.

DESCRIPTION

FIG. 1 is a perspective view showing our new design;

FIG. 2 is a top plan view;

FIG. 3 is a bottom plan view;

FIG. 4 is a first side elevational view;

FIG. 5 is a second side elevational view;

FIG. 6 is a front elevational view; and,

FIG. 7 is a rear elevational view.

Any broken lines denote probable environmental structure and are not part of the claimed design.
